UNITED STATES PATENT OFFICE.

ROBERT NEWTON, OF JERSEYVILLE, ILLINOIS.

LAND ROLLER AND PULVERIZER.

SPECIFICATION forming part of Letters Patent No. 630,467, dated August 8, 1899.

Application filed November 12, 1898. Serial No. 696,286. (No model.)

To all whom it may concern:

Be it known that I, ROBERT NEWTON, a citizen of the United States, residing at Jerseyville, in the county of Jersey and State of Illinois, have invented a new and useful Land Roller and Pulverizer, of which the following is a specification.

This invention relates to a new and useful combined land roller and pulverizer; and it has for its object to effect certain improvements in a machine of this character whereby the same shall be rendered exceptionally strong and capable of adjustment to adapt the same for different uses.

15 To this end the invention primarily contemplates improvements in that type of land rollers and pulverizers employing sectional rollers having what is known in the art as "corrugated" peripheries, whereby the said sectional rollers may be lengthened or shortened according to the use of the machine, while at the same time the separate disks or sections thereof are held closely together in proper working relation.

20 25 With these and other objects in view, which will readily appear when the nature of the invention is more fully understood, the same consists in the novel construction, combination, and arrangement of parts, as hereinabove described, illustrated, and claimed.

30 While the invention is necessarily susceptible to modification, still the preferred embodiment thereof is shown in the accompanying drawings, in which—

35 Figure 1 is a perspective view of a combined land roller and pulverizer embodying the improvements contemplated by the present invention. Fig. 2 is a central longitudinal sectional view thereof. Fig. 3 is a transverse sectional view on the line 3-3 of Fig. 2. Fig. 4 is a detail in perspective of the sectional adjustable roller-frame. Fig. 5 is a detail sectional view showing one of the clamp-yokes embracing the overlapped bars of the frame-sections.

40 45 Like numerals of reference designate corresponding parts in all the figures of the drawings.

50 Referring to the accompanying drawings, the numeral 1 designates an oblong rectangular roller-frame, consisting of the duplicate frame-sections 2, which are adjustably con-

nected together so as to render the frame longitudinally extensible, whereby the same may be lengthened or shortened, according to 55 the size of the rollers which it is desired to use in connection therewith. Each frame-section 2 is of a substantially U shape and consists of the parallel front and rear bars 3 and an end bar 4, connecting the outer terminals of the parallel bars 3, and the said parallel bars 3 of the two U-shaped frame-sections 2 overlap and are adjustably clamped together by means of a plurality of rectangular clamp-yokes 5, provided in their lower 60 sides with the threaded openings 6, receiving the binding-screws 7, which impinge against the lowermost frame-bars 3 and serve to tightly clamp the overlapping parts together.

The contiguous ends of the oppositely-arranged frame-sections 2 overlap each other a considerable distance to strengthen the central portion of the frame, while at the same time permitting of the material adjustment thereof according to the size of rollers required for use, and a pair of the clamp-yokes 5 is preferably employed on the overlapping portions of both front and rear bars 3 of the extensible frame, as plainly shown in Fig. 1 of the drawings. When the clamp-yokes 5 70 are tightened on the overlapping bars 3 of the frame-sections, such frame-sections are held rigidly together; but should it be desired to lengthen or shorten the frame it is simply necessary to loosen the binding-screws 75 80 to accomplish this result.

As the central portion of the frame is subjected to the greatest strain and at times will support from one thousand to three thousand pounds, it is necessary that the same be of 90 exceptional strength, and this reinforcing of the central portion of the machine-frame is accomplished not only by the lapping of the front and rear frame-bars 3, but also through the medium of a pair of central brace-bars 8 95 and 9, arranged transversely of the rectangular frame 1 at a central point between its ends. The central transverse brace-bars 8 and 9 are arranged, respectively, above and below the overlapped portions of the frame-bars 3 of the two frame-sections and are securely clamped to the frame-bars by means of the clamping-bolts 10, arranged in pairs at the front and rear end portions of the said 100

brace-bars 8 and 9 and connecting said bars, respectively, on opposite sides of the overlapping frame-bars, thereby providing an exceedingly-strong bracing of the central portion of the frame. In this connection it will be observed that the clamping-bolts 10 and brace-bars 8 and 9 in effect constitute a central clamp which supplements the action of the clamp-yokes 5 to rigidly hold together 10 the overlapping frame-bars, so that when it is necessary to extend the sectional frame the clamping-bolts, as well as the binding-screws of the clamp-yokes, must be loosened and then retightened after the adjustment has 15 been effected. The front pair of clamping-bolts 10 for the upper and lower transverse brace-bars 8 and 9 also pass through the rear end of the draft-tongue 11, which rests on top of the front end portion of the upper brace-bar 8 and extends to the front in the usual manner, and to provide for the proper bracing of the draft-tongue 11 a pair of brace-rods 12 is employed. These brace-rods are fastened at their front ends, respectively, to 20 opposite sides of the draft-tongue 11 and diverge rearwardly to the front frame-bars 3, to which frame-bars the rear ends of the brace-rods 12 are bolted by means of the securing-bolts 13. These securing-bolts 13 are adapted to be fitted in any of the series of bolt-openings 14, formed in the front frame-bars 3 of the frame-sections 2 in order to permit the frame-sections to be adjusted without disturbing the relative positions of the brace-rods 12. The rear pair of clamping-bolts 10 for the central transverse brace-bars 8 and 9 also pass through the lower end of the seat-support 15, resting on the rear end portion of the upper brace-bar 8 and extending upwardly 25 and rearwardly therefrom at an angle, the upper end of said seat-support or seat-arm 15 supporting thereon the usual driver's seat 16.

The roller-frame carries or supports a single roller-shaft 17, extending longitudinally 45 of the frame the full length thereof and arranged midway between the front and rear frame-bars 3. The said shaft is supported to turn in a plurality of aligned wooden bearing-boxes 18, arranged, respectively, beneath 50 the opposite ends of the roller-frame and the lower central transverse brace-bar 9, and said bearing-boxes are securely braced and held in place by the approximately U-shaped metal straps 19. The metal straps 19 embrace 55 and snugly fit the wooden bearing boxes or blocks 18 and are provided at their terminals with the attaching-flanges 20, which are securely bolted, by means of bolts 21, to the portions of the frame supporting the boxes.

60 At each side of the central pair of transverse brace-bars 8 and 9 the single roller-shaft 17 supports thereon a sectional roller 22, having a corrugated periphery and essentially consisting of a plurality of disk sections 65 23, arranged side by side and closely grouped together and each of which disk sections is provided with a double-beveled or V-shaped

periphery 24, which serves to break the clods or pulverize the soil as the machine is rolled over the ground. The disk sections 23 of each sectional roller are entirely separate and independent of each other, so that the same may be readily removed and replaced, or any number of disk sections grouped together, according to the desired length of the roller; but in the use of the machine it will be understood that each of the sectional rollers 22, respectively, at opposite sides of the transverse center of the roller-frame is preferably of the same length and composed of the same 70 number of disk sections. Furthermore, it will be seen that the central pair of brace-bars 8 and 9 not only serve as a central transverse brace or clamp for the frame, but also form a central abutment for the inner ends 75 of both of the sectional rollers 22, while the outer ends of the U-shaped frame-sections 2 form outer abutments to prevent material separation of the disk sections, so that all 80 of the disk sections of each roller will operate 85 uniformly and in unison as the machine is 90 rolled over the ground.

By reason of the sectional construction of the rectangular roller-frame, whereby the same may be lengthened or shortened, it will 95 be obvious that the adjustment of the frame provides for taking up lost motion or wear of the parts, so that the disk sections of the rollers may always be held close together, so as to prevent trash or soil from working in 100 between the same, and thereby causing the disk sections to work independently and produce an uneven wearing of the parts. An additional advantage of the sectional adjustable construction of frame has already been 105 referred to—viz., to permit additional disk sections to be mounted on the shaft if it is desired to lengthen the rollers, or vice versa; but in all sizes of the sectional rollers it will 110 be understood that the frame-sections are adjusted so as to hold the disk sections closely together, whereby the same may properly 115 subserve their usual function of pulverizing or breaking the clods and evening up the soil.

The opposite extremities of the single continuous roller-shaft 17 are preferably fitted 115 with removable keys 25, whereby the same may be readily removed and replaced; but it will of course be understood that equivalent retaining devices may be used in connection 120 with the shaft for accomplishing the same result without departing from the spirit or principle of the invention.

At this point it will be observed that the openings in all of the bearing boxes or blocks 125 18 are in precise longitudinal alinement; but in view of the lap of the two frame-sections it will be necessary to have the bearing box or block carried by the uppermost frame-section somewhat wider than the other bearing boxes or blocks; as plainly shown in Fig. 2 of the drawings, to compensate for the disalignment or lap of the frame-sections.

From the foregoing it is thought that the

construction, operation, and the many advantages of the herein-described combined land roller and pulverizer will be readily apparent to those skilled in the art without further description and that changes in the form, proportion, and minor details of construction may be made without departing from the spirit or sacrificing any of the advantages of the invention.

Having thus described the invention, what is claimed is—

1. In a machine of the class described, the combination of an extensible frame, comprising two sections having their inner ends overlapping and adjustably connected, and a correspondingly-extensible roller supported by the frame, substantially as set forth.

2. In a machine of the class described, the combination of an extensible frame comprising two sections having their inner ends movably overlapping, and a corresponding extensible roller supported by the frame and consisting of a plurality of independent disconnected disk-sections.

3. In a combined land roller and pulverizer, the combination of an extensible frame having opposite duplicate sections of U-shaped form having their inner ends detachably overlapping, and a sectional roller of variable length supported within each frame-section, substantially as set forth.

4. In a combined land roller and pulverizer, an extensible frame consisting of a pair of duplicate sections overlapping and adjustably clamped together, a central transverse brace clamped upon the overlapped portions of the frame-sections, and a separate roller supported within each of the frame-sections, substantially as set forth.

5. In a combined land roller and pulverizer, an extensible frame consisting of separate oppositely-arranged U-shaped sections having their parallel bars or sections overlapped and adjustably clamped together, a central trans-

verse brace clamped upon the overlapped portions of the frame-sections, and a pair of longitudinally-aligned sectional rollers arranged respectively at opposite sides of the central transverse brace, substantially as described.

6. In a combined land roller and pulverizer, an extensible frame consisting of a pair of duplicate overlapping frame-sections, adjustably connected together, a pair of transverse brace-bars arranged respectively above and below the frame and clamped to the overlapping portions thereof, a single continuous shaft supported at the underside of the frame, and a pair of aligned rollers mounted on the shaft respectively at opposite sides of the transverse brace-bars, substantially as set forth.

7. In a combined land roller and pulverizer, the combination of an extensible frame consisting of a pair of oppositely-arranged duplicate U-shaped frame-sections having their parallel bars or members overlapped, clamp-yokes embracing the overlapped portions of the frame-sections, a pair of transverse brace-bars arranged respectively above and below the frame and clamped to the overlapping portions thereof, a tongue extended from the forward end of the upper transverse brace-bar and having brace-rod connections with the frame-sections, a seat-support extended from the rear end of the upper transverse brace-bar, a single continuous roller-shaft supported at the under side of the frame, and a pair of aligned rollers mounted on said shaft respectively at opposite sides of the transverse brace-bars, substantially as described.

In testimony that I claim the foregoing as my own I have hereto affixed my signature in the presence of two witnesses.

ROBERT NEWTON.
